(57) **CLAIM**

I claim the ornamental design for the golf ball washer, as
shown and described.

DESCRIPTION

FIG. 1 is a perspective view of a golf ball washer;
FIG. 2 is a front elevational view of the golf ball washer;
FIG. 3 is a side elevational view of the golf ball washer, the
opposite side being a mirror image thereof;
FIG. 4 is a back elevational view of the golf ball washer;
FIG. 5 is a top plan view of the golf ball washer; and,
FIG. 6 is a bottom plan view of the golf ball washer.
